his Atty.

UNITED STATES PATENT OFFICE.

JAMES W. MACBOYLE, OF CHICAGO, ILLINOIS.

DESIGN FOR A DOLL.

54,939.

Specification for Design. Patented Apr. 20, 1920.

Application filed October 13, 1919. Serial No. 330,504. Term of patent 14 years.

To all whom it may concern:

Be it known that I, JAMES W. MACBOYLE, a citizen of the United States, residing at Chicago, in the county of Cook and State of Illinois, have invented a new, original, and ornamental Design for Dolls, of which the following is a specification, reference being had to the accompanying drawing, forming a part thereof.

The figure is a view of the doll in elevation, showing my new design.

I claim:

The ornamental design for a doll, as shown.

JAS. W. MACBOYLE.
